[57] CLAIM

The ornamental design for a combined cassette recorder and radio receiver, as shown and described.

DESCRIPTION

FIG. 1 is a front, top and right side perspective view of a combined cassette recorder and radio receiver showing our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a bottom plan view thereof with some of the upper front structure which would be seen omitted for convenience of illustration;

FIG. 7 is a rear elevational view thereof; and

FIG. 8 is a top plan view thereof with the handle pivoted to the rear.
